ROOFING ELEMENT

Thomas Robinson, Smithtown, N. Y., assignor to
 Lancaster Processes Inc., New York, N. Y., a
 corporation of New York

Application November 25, 1936, Serial No. 112,647

12 Claims. (Cl. 108—10)

This invention relates to prepared roofing elements and is concerned more particularly with a novel product differing in construction from and offering numerous advantages over similar elements as now made.

The new product is made of a hardened plastic composition and has a plate-like body which contains a plurality of spaced air chambers within it and lying inwardly from the faces thereof. These air chambers are formed in such a way during the production of the element, that they not only reduce its weight and increase its heat insulating qualities, but also add to its stiffness and rigidity. Because of these latter characteristics, the new product may be made in sizes larger than ordinarily used and laid with an unusually large exposure. Since the spacing between the butts of elements laid in successive courses with the exposure referred to, might in some instances, be objectionable because of the appearance of the roof, I provide the new element with one or more transverse depressions in its upper face and in the exposure area, these depressions having a wall corresponding to and resembling the butt end of the element. The depressions thus give the exposed part of the unit the appearance of being formed of a plurality of units laid with ordinary exposures. The depressions also stiffen the exposed end of the element and reduce any tendency it may have to contract in width.

For a better understanding of the invention, reference may be had to the accompanying drawings in which:

Figure 1 is a plan view of one of the new elements with a portion broken away;

Figures 2 and 3 are sectional views on the lines 2—2 and 3—3, respectively, of Figure 1;

Figure 4 is a sectional view on the line 2—2 of Figure 1, but illustrating a modified form of the element of the invention;

Figure 5 is a sectional view through a roof made of the elements illustrated in Figure 4; and

Figures 6, 7, and 8 are plan views of roofs showing the manner of application of the new elements.

The new roofing product is made of a hardened plastic material, such as a fibrous bituminous mastic, and I prefer to employ for the purpose the composition described and claimed in my co-pending application, Serial No. 54,714, filed December 16, 1935, now Patent No. 2,072,636. The composition referred to consists of asphalt of a suitable melt point, water, and a stabilizing

agent combined to form an emulsion in which the asphalt is in the continuous phase and water is in the disperse phase, and fibrous material, such as natural wood disintegrated to the form substantially of elementary fibres or small fibre bundles, distributed substantially uniformly and homogeneously therethrough.

In the formation of the new product, the plastic material is shaped, preferably by an extrusion operation, to the form of a sheet of uniform thickness and of indefinite length having spaced air chambers within it, the product so formed being that disclosed in my co-pending application Serial No. 112,478, filed November 24, 1936. This sheet is then cut into units of desired sizes and subjected to final shaping operations.

The roofing element illustrated in Figure 1 is produced by the method described and it includes a plate-like body 10 which may be of any suitable dimensions, such, for example, as from two feet to four feet wide, and from two feet to four feet long, and of any desired and appropriate thickness. Within the body is a series of spaced parallel air chambers 11 which are preferably round or oval in cross-section and spaced inwardly a substantial distance from the upper and lower faces of the body. Thus, as illustrated in Fig. 3, the vertical dimension of the chambers may be about one-half the thickness of the body, and each of the layers 12 and 13 of material lying, respectively, above and below the chambers may have a thickness equal to about one-quarter of that of the body. The chambers lie with their axes in a central plane through the body and extend substantially from one end of the body to the other. At its ends 14 and 15, the body may be provided with end walls partially or completely closing the ends of the chambers and at the end 15, which is the end of the element to be exposed when the element is laid in the usual way, and may, therefore, be considered the butt end, the end wall preferably completely closes the chambers and provides an integral connection between the upper and lower layers 12, 13. The body has generally flat upper and lower faces and may be of uniform thickness throughout the portion 16 which is to be overlaid by the elements of higher courses, or it may be tapered, as indicated at 17 in Fig. 4.

When a roofing element having a length of 2 feet is laid with the usual 3 inch head-lap, the exposure is approximately 10½ inches, and this exposure may be objectionable with respect to the appearance of the roof, in the case of small

buildings. Accordingly, the new roofing element is so formed that, although it may be laid with the unusually large exposure referred to, it gives the roof the appearance of being covered with roofing elements laid with the normal exposure. This result is attained by forming one or more depressions 18 in the upper face of the element adjacent the butt end, the elements illustrated in the drawing having two such depressions. 5 These depressions extend across the element from side to side and lie generally parallel and, if desired, the depressions may be straight, as indicated at 19 (Fig. 7), or may be wavy, as indicated at 20 (Fig. 1), the butt end edge being 10 also wavy in the latter case. 15 The depressions referred to are formed by applying pressure to the body by suitable means while the mastic is warm and plastic, and in the formation of the depressions, the walls of the air chambers beneath them are forced together to such an extent that the air chambers are partially or completely interrupted. Preferably, the pressure applied to form the depressions is such that the upper and lower walls of the chambers are 20 forced into contact and become substantially merged, and the means employed for applying pressure to the upper face of the elements in the formation of the depressions is so shaped that each depression has a wall 21 remote from the 25 end wall 15 of the element, which closely resembles that end wall in appearance. After the units have been formed as described, they are finished by the application of suitable surfacings. Thereafter, they are allowed to harden and are then 30 ready for use. 35

In covering a roof with the new elements, they may be laid in various ways as, for example, the elements may be placed side by side in overlapping courses, as indicated in Fig. 6, with the joints 40 22 between the elements 23 in each course covered by elements 24 in the next higher course. Preferably, the elements of the third course 25 are so applied as to overlie the elements in the second lower course, thus providing head-lap. In laying 45 the elements in a course, adjacent elements are so placed that their end edges 26, 26 are in substantial alignment, and the ends of their corresponding depressions 27, 27 are substantially in registry. The ends 28 of the elements of the next higher 50 course are then spaced from the highest depressions in the elements of the course beneath by a distance approximating that between adjacent depressions in each element. When the entire roof is covered with elements applied in this manner, the aligned depressions cast substantially the 55 same shadow as the exposed ends of the elements so that the roof has the appearance of being covered by a great many elements laid in courses and with relatively small exposure. Also, if the elements have wavy depressions and similar butt ends, the roof has the general appearance of a 60 thatched roof.

The appearance of a roof covered with elements having straight butt ends and depressions is illustrated in Fig. 7 and it will be noted that a roof so formed has the appearance of one covered with ordinary roofing elements laid with the usual relatively small exposure.

Instead of laying the elements as illustrated in Figs. 6 and 7, the method shown in Fig. 8 may be employed, in which the elements of each course, such as those designated 29, are overlapped only by the elements of one higher course, as indicated by the element 30. In this case, the joint 31 between a pair of adjacent elements is protected by 75

a strip 32 of roofing felt, or the like, applied before the elements are placed in position. Also, for a roof of this type, the elements need not be so long, or, if desired, elements of the same length as those previously described may be employed, but with more than two transverse depressions per element. 5

The new element containing the air chambers is relatively stiff and rigid and in those respects resembles the chambered sheet material described in my copending application, Serial No. 112,478, filed November 24, 1935. It also has excellent insulating qualities because of the presence of the air chambers within it, and the formation of the depressions across the air chambers both adds to the strength of the element and lessens its tendency to contract in width with changes in temperature conditions. 10 15

Since the new element may be laid with greater than normal exposure, it may be applied at less expense, because, for a given roof area, fewer elements are required to be laid and fewer nails to be driven. Also, the roof thus produced has less joints and the possibility of leakage is thereby reduced. The new material is cheap and easy to manufacture and the several advantages resulting from the possibility of laying it with greater exposure are not gained in any way at the expense of the appearance of the roof. 20 25

While I have described the roofing element of the invention as comprising a plate-like body having air chambers within it and spaced inwardly from the faces thereof, many of the advantages of the invention can be obtained by forming the body with air chambers which are open through one face of the body, preferably the face to be laid downward. With such a construction, the chambers form channels in the under side of the element. Similarly, the depressions in the upper surface of the element can be employed in connection with elements which do not have air chambers, but a chambered element is preferred since it is stiffer and lighter than a solid element of the same dimensions. 30 35 40

I claim:

1. A roofing element which comprises a plate-like body of hardened plastic material provided with a series of spaced parallel air chambers within it between the faces thereof, said body having a depression extending across it adjacent one end thereof, portions of the chambers lying between said end and the depression. 45 50

2. A roofing element which comprises a plate-like body of hardened plastic material provided with a series of spaced parallel air chambers within it between the faces thereof, said body having an end wall substantially closing the chambers and having a depression in its upper face extending across it adjacent said end wall, portions of the chambers lying between said end and the depression. 55 60

3. A roofing element which comprises a plate-like body of hardened plastic material provided with a series of spaced parallel air chambers within it between the faces thereof, said body having an end wall substantially closing the chambers and having a depression in its upper face extending across it adjacent said end wall, the wall of said depression remote from said end wall having substantially the same appearance as said end wall and portions of the chambers lying between the depression and said end wall. 65 70

4. A roofing element which comprises a plate-like body of hardened plastic material provided with a series of spaced parallel air chambers 75

within it between the faces thereof, said body having a transverse depression in one face adjacent one end thereof, said chambers being interrupted beneath said depression. 5

5. A roofing element which comprises a plate-like body of hardened plastic material provided with a series of spaced parallel air chambers within it between the faces thereof, said body having a transverse depression within that portion of the face of the body which is exposed 10 when the element is laid in the usual way with others in overlapping courses, the chambers each being interrupted by the depression.

6. A roofing element which comprises a plate-like body of hardened plastic material provided with a series of spaced parallel air chambers within it between the faces thereof, said body having a plurality of generally parallel transverse 15 depressions within that portion of the face of the body which is exposed when the element is laid in the usual way with others in overlapping courses, the chambers each having one wall deformed beneath the depressions.

7. A roofing element which comprises a plate-like body of hardened plastic material provided with a plurality of series of spaced parallel air 20 chambers within it between the faces thereof, the chambers of each series lying in alignment with those of the adjacent series and said body having a depression in one face in registry with the space between adjacent series of chambers.

8. A roofing element which comprises a plate-like body of hardened plastic material provided with a plurality of spaced parallel air chambers within it between the faces thereof, the body having a generally flat upper face and an end wall substantially closing the air chambers, said face having a depression extending across it adjacent 25 said end wall with the bottom of the depression lying below the tops of the air chambers in the body at one side of the depression.

9. A roofing element which comprises a plate-like body of hardened plastic material and of decreasing thickness from one end of the body

toward the other, said body having a plurality of spaced parallel air chambers within it between the faces thereof and a wall at the thick end of the body substantially closing the chambers, said body also having a depression extending across 5 it in its upper face adjacent the thick end.

10. A roof formed of a plurality of roofing elements laid side by side in overlapping courses, each of said elements comprising a plate-like body of hardened plastic material having a plurality of spaced parallel air chambers within it between the faces thereof and having at least one transverse depression in its upper face and in that part of said face lying exposed by the elements in the next higher course, the chambers 10 being interrupted beneath said depression, the adjacent elements in each course lying with their exposed ends in substantial alignment and with the ends of their depressions substantially in 15 registry.

11. A roof formed of a plurality of roofing elements laid side by side in overlapping courses, each of said elements comprising a plate-like body of hardened plastic material having a plurality of spaced parallel air chambers within it 20 between the faces thereof and having two spaced transverse depressions in its upper face, the chambers being interrupted beneath each depression, each course of elements being laid to expose both depressions in the elements of the next 25 lower course beyond the ends of the elements in the higher course and the elements in each course lying with their exposed ends in substantial alignment and with the ends of their depressions substantially in 30 registry.

12. A roofing element which comprises a plate-like body of hardened fibrous bituminous mastic having a plurality of spaced air chambers within it between the faces thereof and a depression extending across the body in the upper face thereof 35 adjacent one end, the chambers being collapsed beneath said depression.

THOMAS ROBINSON.
